UNITED STATES PATENT OFFICE.

JOHN L. SOMMER, OF NEWARK, NEW JERSEY.

SHOE BUTTONER AND HORN.

No. 841,192.

Specification of Letters Patent.

Patented Jan. 18, 1907.

Application filed May 23, 1906. Serial No. 318,287.

To all whom it may concern:

Be it known that I, JOHN L. SOMMER, a citizen of the United States, residing at Newark, in the county of Essex and State of New Jersey, have invented certain new and useful Improvements in Shoe Buttoners and Horns, of which the following is a specification.

The objects of this invention are to combine in a single implement a shoe-horn and shoe-buttoner, to secure a simple and yet secure fastening of the two parts together, to provide such a construction which shall be convenient and comfortable to the grasp, to save cost and labor in the manufacture, and to obtain other advantages and results as may be brought out in the following description.

Referring to the accompanying drawings, in which like numerals of reference indicate corresponding parts in each of the several figures, Figure 1 is a front view of my improved device, and Fig. 2 is an edge view of the same. Fig. 3 is a detail view of a portion of the implement from its rear to show the manner of joining more clearly, and Fig. 4 illustrates the manner of grasping the device in the hand.

In said drawings, 1 indicates the shank portion of the shoe-buttoner, having the usual curved or bent extremity 11.

2 indicates the body portion of a shoe-horn which at its small end has a tongue 3, curved or returned upon the back or convex side of the said shoe-horn. The said tongue 3 is perforated, as at 4, at its point 5 of bending, as shown clearly in the drawings, and through this perforation 4 is passed the shank 1 of the shoe-buttoner, said shank fitting the perforation tightly. The end of the shank is flattened and curved, as at 6, to lie against the back of the shoe-horn 2, and the extremity of the tongue 3 is bent to lie, as at 7, upon the said flattened extremity 6 of the buttoner-shank. A rivet 8 is then passed through said extremity 7 of the tongue, flattened end 6 of the shoe-buttoner, and body portion of the shoe-horn, thus binding all the parts firmly and rigidly together. Preferably the said tongue 3 is tapered, being quite broad at its

base, so as to secure sufficient strength against lateral strain, and thus it will be clearly apparent that the shoe-buttoner is held at two separated points with great firmness and rigidity, so that by the insertion of the single rivet the two parts—shoe-buttoner and shoe-horn—are securely connected.

Great simplicity and ease of manufacture are secured, and at the same time a completed article is produced which will not work loose or yield in the hands of the user.

60

The tongue 3 at its bend 5 is carried outward from the body of the shoe-horn, as shown in the drawings, and then at its extremity 7 brought closer to the shoe-horn, and this provides in the use of the implement 65 a finger-hold or enlargement which lies between the forefinger and thumb in grasping the implement and gives a firm hold, as clearly shown in Fig. 4 of the drawings. Obviously the flattening of the shank of the 70 shoe-buttoner at 6 enables the enlargement of the curve of the tongue to be made more pronounced.

The shoe-horn is preferably made of sheet metal, such as is commonly used for those articles, and the other member or buttoner is of wire properly drawn and shaped into the form described. Great cheapness and simplicity are thus secured in the device.

Having thus described the invention, what 80 I claim as new is—

1. A shoe-horn having a tongue at the small end thereof bent backward upon itself and perforated at the point of bending, and a button-hook having a shank passed through 85 said perforation, and a rivet through said tongue, shank and shoe-horn.

2. The combination of a shoe-horn, having an integral tongue at its small end returned or bent backward, and perforated at the point 90 of bending, a shoe-buttoner having a shank lying in said perforation and a flattened extremity beyond the same lying between the shoe-horn and its tongue, and a rivet through said tongue, flattened shank and shoe-horn. 95

3. The combination of a shoe-horn, having at its small end an integral tongue curved backward at a distance from the body portion of the shoe-horn and brought at its extremity adjacent to the same, a shoe-buttoner having its shank passed through said tongue at its point of curvature, and a rivet through said tongue, shank and shoe-horn, the rounded or swelled end of said tongue providing a finger-grasp.

4. The combination of a sheet-metal shoe-horn having at its small end an integral tongue bent backward upon itself and perforated at the point of bending, and a wire member fitting the perforation in said tongue 110 and extending between the end of the tongue and the body of the shoe-horn, said end of

105

110

the tongue and the underlying wire member being secured to the shoe-horn body at that point.

5. The combination of a sheet-metal shoe-horn having at its small end an integral tongue curved outwardly backward and brought at its extremity closer to the body of the shoe-horn, said tongue being perforated at its said bend, and a wire member fitting the said perforation and having a flattened portion beyond the same lying between the

end of the tongue and the body of the shoe-horn, whereby said end of the tongue closely approaches the shoe-horn body and its rounded portion provides an enlarged finger-grasp, said end of the tongue and underlying flattened portion of the wire member being secured to the shoe-horn body at that point. 15
